TOILET SEAT

Francis J. Moore, Minneapolis, Minn.

Application March 15, 1939, Serial No. 261,941

6 Claims. (Cl. 4—240)

My present invention relates to toilet seats and more particularly to a divided toilet seat, and has for its object to provide an extremely simple and highly efficient means for mounting said seat on a toilet bowl, whereby the sections thereof may be independently moved toward or from each other to adjust the seat for an adult or a child. The improved mounting of the seat sections also permits said sections to be independently raised or lowered. The invention also provides a simple and efficient means for holding the seat sections against movement toward each other when adjusted for an adult.

To the above end the invention consists of the novel devices and combinations of devices hereinafter described and defined in the claims.

In the accompanying drawings, which illustrate the invention, like characters indicate like parts throughout the several views.

20 Referring to the drawings:

Fig. 1 is a plan view showing a divided toilet seat mounted on a toilet bowl by means of this invention, some parts being broken away, and other parts shown in different positions by means 25 of broken lines;

Fig. 2 is a side elevation of the parts as shown in Fig. 1, with the seat sections, fragmentarily shown by means of broken lines, in a raised position;

30 Fig. 3 is a bottom plan view of the right hand hinge member, as shown in Fig. 4, attached to a fragment of the respective toilet seat section;

Fig. 4 is a plan view, on an enlarged scale, of the invention removed from the toilet bowl, and 35 with the seat sections removed therefrom;

Fig. 5 is a view partly in rear elevation and partly in section, taken on the line 5—5 of Fig. 4;

Fig. 6 is a view partly in elevation and partly 40 in section, taken on the line 6—6 of Fig. 5, with a fragment of the respective seat section attached thereto; and

Fig. 7 is a fragmentary view of the parts, as shown in Fig. 5, and further showing means for holding the hinge members against movement toward each other when in their extreme separated position.

The numeral 8 indicates a toilet bowl on which 45 is mounted, by means of my invention, a toilet seat comprising two seat sections 9 of the type disclosed and broadly claimed in my pending application for U. S. Letters Patent, filed Jan. 12, 1939, under S. N. 250,512, and entitled "Toilet seat."

The improved device for mounting the seat sections 9 on the bowl 8 includes a pair of bolts 10

which extend through apertures in said bowl. These bolts 10 have intermediate heads 11 and washers and nuts 12 are applied to their lower end portions, which anchor said bolts to the bowl 8. Formed in the bolts 10 above the heads 11 5 is a pair of horizontally aligned eyes 13.

A steel hinge rod 14 is mounted in the eyes 13 for turning movement about its longitudinal axis. The end portions of the hinge rod 14 extend outwardly of the bolts 10 and a nut 15 is 10 applied to each end thereof. A long sleeve 16 is telescoped onto the hinge rod 14 between the bolts 10 and held by said bolts against endwise sliding movement on said rod. Relatively short sleeves 17 are telescoped onto the end portions 15 of the hinge rod 14, one between each bolt 10, and the respective nut 15, and held thereby against endwise sliding movement on said rod.

A pair of hinge members 18 are secured, one to each seat section 9, at its rear end portion, 20 on the under side thereof, by means of screws 18'. Each hinge member 18 has, integral with its rear longitudinal edge portion, a pair of axially spaced hinge lugs 19. The two inner hinge lugs 19 are turnably mounted on the sleeve 16 25 and the two outer hinge lugs 19 are turnably mounted on the two sleeves 17.

The bolts 10 extend between the hinge lugs 19 of the two pairs and act as stops for the hinge members 18, and hence the seat sections 9. During 30 separating movement of the seat sections 9, the inner pair of hinge lugs 19 engage the bolts 10 as stops and limit said movement. The movement of the seat sections 9 toward each other is limited by the engagement of the outer pair 35 of hinge lugs 19 with the bolts 10. Obviously, the pairs of hinge lugs 19 are free to independently turn on the sleeves 16 and 17 about the axis of the hinge rods 14 and are also free to independently slide axially on said sleeves. This 40 mounting of the hinge lugs 19, on the sleeves 16 and 17 permits the seat sections 9 to be independently raised or lowered or independently moved toward or from each other.

When the seat sections 9 are adjusted for an 45 adult they may be positively held in this position by a stop sleeve 20 telescoped onto the sleeve 16, see Fig. 7. The ends of the stop sleeve 20 engage the inner pair of hinge lugs 19 and hold the same against the bolts 10 so that said hinge 50 lugs cannot slide axially on the sleeve 16 but are free to turn about the axis thereof.

From the above description, it is evident that the above described invention is extremely simple, easy to assemble and to keep clean.

The drawings illustrate a commercial form of the invention, but it will be understood that the same is capable of certain modifications as to details of construction, arrangement and combination of parts within the scope of the invention herein disclosed.

What I claim is:

1. A device of the kind described comprising a pair of eye-bolts for anchoring the device to a toilet bowl, a hinge rod mounted in the eye-bolts with its end portions extending outwardly thereof, an intermediate sleeve telescoped onto the hinge rods between the eye-bolts, a pair of end sleeves telescoped onto the hinge rod outwardly of the eye-bolts, and a pair of hinge members having means for attaching the same to the sections of a divided toilet seat, each hinge member having a pair of axially spaced lugs between which one of the eye-bolts extends, said lugs being more widely spaced than the axial length of the eye-bolts and being mounted on the sleeves for independent turning movement and independent axial sliding movement, said hinge lugs engaging the eye-bolts as stops to limit the movement of the hinge members toward or from each other.
2. The structure defined in claim 1 which further includes a nut applied to each end of the hinge rod, the eye-bolts and the nuts holding the sleeves against axial sliding movement on the hinge rod and said sleeves in turn holding the hinge rod against endwise sliding movement relative to the eye-bolts.
3. The structure defined in claim 1 which further includes a stop sleeve telescoped onto the intermediate sleeve and holding the inner hinge lugs between the eye-bolts and the ends of the stop sleeve to prevent axial sliding movement of the hinge lugs on the intermediate and end sleeves.
4. A toilet set hinge construction comprising a pair of spaced eye-bolts for anchoring to a toilet bowl, a hinge rod mounted in the spaced eye-bolts with its end portions projecting outwardly thereof, an intermediate sleeve enclosing the hinge rod between the eye-bolts and having opposite ends engageable with the inner ends of the respective eye-bolts, a pair of end sleeves enclosing the projecting end portions of the hinge rod outwardly of the eye-bolts and having inner ends

engageable with the outer ends of the respective eye-bolts, a pair of toilet seat connecting hinge means each comprising a lug mounted on the center sleeve and a lug mounted on one of the end sleeves, the lugs being axially more widely spaced than the axial length of the eye-bolts, and means on the hinge rod engageable with the lugs of the pair of hinge means.

5. A hinge structure of the class described for a toilet seat comprising a pair of spaced eye-bolts for anchoring to a toilet bowl, a hinge rod mounted in the spaced eye-bolts with its end portions projecting outwardly thereof, an intermediate sleeve enclosing the hinge rod between the eye-bolts and having opposite ends engageable with the inner ends of the respective eye-bolts, a pair of end sleeves enclosing the projecting end portions of the hinge rod outwardly of the eye-bolts and having their inner ends engageable with the outer ends of the respective eye-bolts, a pair of toilet seat connecting hinge means each comprising a lug mounted on the center sleeve and a lug mounted on one of the end sleeves, the lugs being axially more widely spaced than the axial length of the eye-bolts, and stop means on the intermediate sleeve engageable with the lugs for limiting axial movement of the hinge means toward each other.

6. A hinge structure of the class described for a toilet seat comprising a pair of spaced eye-bolts for anchoring to a toilet bowl, a hinge rod mounted in the spaced eye-bolts with its end portions projecting outwardly thereof, an intermediate sleeve enclosing the hinge rod between the eye-bolts and having opposite ends engageable with the inner ends of the respective eye-bolts, a pair of end sleeves enclosing the projecting end portions of the hinge rod outwardly of the eye-bolts and having their inner ends engageable with the outer ends of the respective eye-bolts, a pair of toilet seat connecting hinge means each comprising a lug mounted on the center sleeve and a lug mounted on one of the end sleeves, the lugs being axially more widely spaced than the axial length of the eye-bolts, and a sleeve enclosing the intermediate sleeve in its central portion engageable with the lugs for limiting axial movement of the hinge means toward each other.

FRANCIS J. MOORE.
